Fig. 4A.

Fig. 4 B.

Fig. 4c.

Fig. 1 is a full scale, fragmentary plan view of the plastic coated sheet material of our new design and showing that portion enclosed within the dot and dash lines of Fig. 4A in detail;

Fig. 2 is a vertical sectional view of the fragment of plastic coated sheet material of Fig. 1 taken along line II—II;

Fig. 3 is a fragmentary sectional view, on an enlarged scale, taken along the line III—III of Fig. 1; and

Figs. 4A, 4B, and 4C, taken together by placing the lines A—A' and B—B' in juxtaposition, constitute a plan

view of the plastic coated sheet material of our new design on a reduced scale showing a complete design unit with extensions beyond the unit boundaries as indicated by the marks at the top and bottom of the figure.

We claim:

The ornamental design for a plastic coated sheet material, substantially as shown and described.
